ATTORNEY

UNITED STATES PATENT OFFICE.

JOSEPH KUDNER, OF NEW YORK, N. Y.

DISPLAY STAND.

1,423,226.

Specification of Letters Patent.

Patented July 18, 1922.

Application filed March 20, 1922. Serial No. 545,023.

To all whom it may concern:

Be it known that I, JOSEPH KUDNER, a citizen of the United States, residing at the city of New York, borough of Manhattan, in the county of New York and State of New York, have invented certain new and useful Improvements in Display Stands, of which the following is a specification.

This invention relates to display apparatus and has particular reference to stands or tables upon which various commodities in loose or bulk form may be exhibited to the best possible advantage.

Among the objects of the invention is to provide means for supporting in a removable or interchangeable condition or position a series of individual pans or trays in which are held various commodities for display or exhibition purposes. I wish it to be understood however that the invention is not to be restricted in its interpretation to any particular specific use or in connection with any special line of goods to be displayed.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a perspective view indicating the general nature of the improvement in practice.

Fig. 2 is a bottom plan view of the main upper portion of the stand.

Fig. 3 is a vertical section showing in full lines the relation of the top to the pedestal, as in Fig. 1, and in dotted lines the folded position of the top.

Referring now more specifically to the drawings 10 indicates a base upon which is supported a pedestal 11, both of any suitable design or construction, the latter however having a head 12 having a transverse pivot hole 13 through which is fitted a clamping or pivot bolt 14.

The top includes a plate 15 of any suitable form in outline but made preferably of wood or its equivalent and to which are secured a pair of brackets 16 forming bearings for the ends of the bolt 14 and through which the top structure is pivotally and ad-

justably secured to the pedestal head. The bolt includes a thumb nut 17 or its equivalent for clamping the brackets against the sides of the head 12 for holding the top in a level position or in any other position than that in which it is shown in Figs. 1 and 3.

Secured in any suitable manner upon the top of the plate 15 is a holder 18 made preferably of sheet material and indicated as 65 made from a circular piece of metal but provided from its periphery with a series of slits 19 extending radially inward toward the center, thereby forming a series of pairs of ears which when turned up at right 70 angles to the main portion of the holder constitute members to embrace the sides of and for holding a series of detachable and interchangeable pans or trays 20 of any suitable form or construction, the same however being shown as diamond shaped and six in number to fill the entire holder. As already suggested these trays are designed to be filled or supplied with various kinds of commodities for display purposes, such as groceries in a grocery store or candy in a candy store, and so on. Each tray may include a transparent cover or closure if desired.

The length of the trays radially of the holder 18 is greater than the radius of the 85 holder, so that the outer end of each tray projects somewhat beyond the periphery of the holder. As indicated said outer end of the tray is pointed similarly to the inner end, but obviously the outer end might be 90 otherwise formed and yet the operation would not be essentially different from that set forth herein. As shown the sides of each tray are embraced by a pair of ears 18^a adjacent to the mid portion of the tray 95 and just outside of the center line thereof, so that the bulk of each tray is held directly upon the upper surface of the holder. The ears prevent the tray from slipping either laterally or outwardly. The inner ends or 100 points of the trays are slipped beneath the flat head of a center pin or screw 21 the shank of which extends downward through the center of the holder and the center of the plate 15 and is adapted to impinge 105 against the head 12 of the pedestal on one side of the vertical axis of the pedestal so as to limit the tilting of the top structure in one direction. Said head however is so reduced at 12' on the other side of the pivot 110 as to permit the top to swing over in the other direction into a vertical plane, a very

important consideration for storage purposes. The trays, as above premised, may be filled with any specified commodities that are to be displayed and being loose in their seats on the support or holder may easily be lifted off or interchanged at any time. In putting a tray into its place on the holder the inner end or point thereof is slipped beneath the head of the pin 21 so that the side corners or shoulder portions of the tray will slip downward between the ears 18°.

I claim:

1. The herein described display stand comprising a holder, a pin in the central portion of the holder and having a head spaced from the holder for engaging a series of interchangeable trays, and means at the periphery of the holder to engage and embrace the outer portions of the trays while the inner ends of the trays are located beneath the head of said pin.
2. In a display stand, the combination of a pedestal, a top, means to connect the top

to the upper portion of the pedestal, said 25 top comprising a holder, a plate beneath the holder, and means including a center screw for holding the plate and the holder together, said screw projecting beneath the plate and serving as a positive stop to limit 30 the tilting of the top in one direction.

3. In a display stand for a series of interchangeable commodity trays, a holder for said trays comprising a circular sheet of material slitted radially inward from its 35 periphery between each two trays and having the peripheral portions of the sheet turned at right angles to the main portion thereof away from each slit to form tray engaging ears.

4. A device as set forth in claim 3 in which a center pin having a head spaced from the holder is provided for engagement over the inner contiguous ends of the trays while the trays are held by the ears afore- 45 said.

In testimony whereof I affix my signature.

JOSEPH KUDNER.
